SCORING DEVICE FOR PUNCHING AND REMOVING CHIPS FROM COMPUTER PUNCH CARDS

HISTORICAL BACKGROUND

For many years, computer punch cards have been available which are scored in such a manner as to provide a plurality of rows of rectangles thereon which may or may not have identifying indicia. These cards are used in such a manner that the rectangles form chips of cardboard, or the like once they have been punched out along the score lines. One of the problems of present day equipment for removing the rectangular chips is that they tend to hinge on side or the other and not break free from the card. Thus, when the cards are stacked, some of the chips which have not been completely removed, because of the hinge, tend to return to the hole from which they were struck. It is quite obvious, that someone endeavoring to read the information which has been placed on the card, could well be in error since they might not observe that one of the rectangular chips though punched, has not been punched completely out.

Inadequate punching equipment has caused numerous errors and frequent backchecking to determine whether or not there are any chips which are hinged so that they can be removed prior to scoring. For the most part, machines which have been manufactured with the intent of completely removing the chips, are expensive and not foolproof.

Elaborate and costly means have been developed to insure removal of the chips in order to eliminate error. Frequently, the equipment must be operated rather slowly to insure complete removal of the chips. Where the scoring of the cards is done by manual means, a careful check must be made to eliminate the problem aforementioned. In many instances, this check must be done visually and the chips removed by hand.

OBJECTS AND SUMMARY

It is therefore an object of this invention to provide a machine or device for punching and removing chips from computer punch cards which is simple and inexpensive to manufacture.

Another object of this invention is to provide a scoring device for removing chips from computer punch cards by manual means.

A further object of this invention is to provide a scoring device for punching and removing chips which at all times insures proper removal of the chip without hinging of the chips.

Still another object of this invention is to provide a device for punching and removing chips from computer punch cards which will electrically indicate the specific punch being used in order to properly score the card passing beneath the punches.

Still a further object of this invention is to provide a scoring device which has means for punching and removing the chips as well as means for receiving and collecting the chips.

Another object of this invention is to provide a scoring device which has means for aligning a typical card prior to the beginning of the scoring operation.

Yet a further object of this invention is to provide a scoring device for punching and removing chips from computer punch cards which includes movable and changeable indicia bearing apparatus.

Yet a further object of this invention is to provide a scoring device for removing punched chips from computer punch cards which incorporates more than one bank of punches. The first punching mechanism may be for the purposes of identification of the individual utilizing the equipment. The second punching mechanism is mounted above the first punching mechanism and utilized for the purpose of punching secondary information on the card.

Yet a further object of this invention is to provide a scoring device for punching and removing chips from computer punch cards which has no working parts.

These and other objects of this invention will be apparent from a reading of the following description and claims:

In the accompanying drawings which illustrate the various embodiments of the invention:

FIG. 1 is a perspective view showing a typical scoring device as taught by the invention;

FIG. 2 is a cross-sectional view taken along the lines 1-2-2 in FIG. 1 and viewed in the direction of the arrows;

FIG. 3 is a schematic view illustrating the punch operating to remove a chip;

FIG. 4 is a cross-sectional view in side elevation illustrating yet another embodiment of this invention;

FIG. 5 is a fragmentary cross-sectional view taken along the lines 5-5 in FIG. 4 and viewed in the direction of the arrows;

FIG. 6 is a fragmentary cross-sectional view with certain portions of the device removed to illustrate still another embodiment of this invention;

FIG. 7 is an enlarged cross-sectional view taken along the lines 7-7 in FIG. 6 and viewed in the direction of the arrows;

FIGS. 8 and 9 are fragmentary cross-sectional views primarily in schematic illustrating still another embodiment of the upper portion this invention which could be used with the lower portions shown in FIGS. 3, 5, or 16.

FIG. 10 is an end view of the invention taken along the lines 10-10 and viewed in the direction of the arrows;

FIGS. 11 and 12 are fragmentary side elevational views of another embodiment of this invention which could be used with the lower portions shown in FIGS. 3, 5, or 16 with FIG. 11 showing the upper position of the punch prior to operation and FIG. 12 showing the lower position of the punch during operation;

FIG. 13 is a front elevational view of the embodiment of this invention illustrated in FIG. 12 taken along the lines 13-13 and viewed in the direction of the arrows;

FIG. 14 is a top plan view taken along the lines 14-14 in FIG. 12 and viewed in the direction of the arrows;

FIG. 15 is a fragmentary cross-sectional view of still another embodiment of this invention;

FIG. 16 is an enlarged fragmentary view taken along the lines 16-16 in FIG. 15 and viewed in the direction of the arrows;

FIG. 17 is a fragmentary plan view illustrating another embodiment of the punching key as taught by this invention;

FIG. 18 is a side elevation view taken along the lines 18-18 of FIG. 17 and viewed in the direction of the arrows;

FIG. 19 is a fragmentary cross-sectional view with portions removed illustrating means for identifying a card which may be inserted therein.

FIGS. 1 THROUGH 3

In FIG. 1, the scoring device includes a card holder generally shown at H. A card C as best shown in FIG. 2, is fed into a slot 10 in the rear of the card holder H. The slot is formed by upper holding or restricting means 12 and 14 and lower support means 16 and 18. Sidewalls 20 and 22 position the upper holding means 12 and 14 and lower support means 16 and 18. An opening or slot 24 is formed between the lower support means 16 and 18. Mounted to project slightly into the slot or opening 24 is a feed roller 26 having an external manipulating knob 28 as best illustrated in FIG. 1. The feed roller 26 preferably is of resilient material and preferably is knurled or corrugated lengthwise. Mounted beneath the roller 26 is a chip receptacle 30.

The upper holding or restricting means 12 is provided with a bore 32 (FIG. 2) which matches with an opening 34 (FIG. 1) for holding a punch stylus 36 which is held captive to the sidewall 22 by means of a chain or the like 38.

The upper holding or restricting means 14 is provided with a series of parallel coextensive slots 40. In FIG. 2, it will be noted that the rear face of the slot 42 is positioned above the feed roller 26 and slightly forward of the axis of the feed roller 26.

The front wall 44 of the slot 40 extends beyond the outer periphery of the roller 26.

Mounted in advance of the upper restricting means 12 is an indexing roller 46 having various indicia thereon for identifying the parallel coextensive slots 40 and thus for determining different informational series which might be selected for scoring the card C. A knob 48 is provided for rotating the indexing roller 46 to present different indicia depending upon the type questions which are to be answered and scored on the card C.

Adjacent the slots 40 is a visual aligning slot or transparent guide 50 which permits the operator of the card holder H to position the card initially within the holder H so that the scored rectangular portions of the card C will be positioned properly beneath the openings or slots 40 whereby the punch stylus 36 will operate directly to remove the chips 52 from the card C.

In FIG. 3, it will be noted that the stylus 36 includes a punch 54 which is spring biased by a spring 56.

OPERATION

It will now be obvious that when the punch 54 of the stylus 36 is fed into one of the slots 40, and the card C has been positioned in such a manner that the rectangular chips are directly aligned with the slot 40, the punch 54 will engage the chip 52 and force it against the resilient roller 26. Since the pressure of the stylus will be slightly off center of the roller 26, the roller will rotate in a clockwise direction as illustrated in FIG. 3. In doing so, the chip 52 will be clamped between the roller 26 and the punch 54 and will be stripped from the card C. The rotation of the roller 26 will also cause the stylus 36 to be moved forwardly in the slot 40 toward the front wall 44 and in so doing will advance the card C the exact distance necessary to present a new scored rectangular chip 52 for a new punching operation. The spring 56 allows the punch 54 to recoil slightly thereby permitting a constant pressure on the roller 26 without severely damaging the roller 26 to thus provide long life for the roller 26.

As the chips are stripped from the card C, they drop into the chip receptacle 30 which is removable for disposing of the chips which have collected therein. It is to be noted that the punch 54 can only travel downwardly into the slots 40 up to the barrel portion of the punch stylus 36. Thus the stylus 36 is limited both in downward travel by the width of the slot 40 and in forward travel by the front wall 44 of the slot 40.

FIGS. 4 AND 5

FIGS. 4 and 5 show a slightly different feeding mechanism which can be utilized within the card holder. The upper holding and restraining means 12 and 14 are identical to the structure illustrated in FIGS. 1 through 3. However, a lower support means 58 comprises a piece of flat sheet material from which has been struck downwardly beneath the slots 40 a series of ramps 60. The ramps 60 may be grooved as illustrated. In effect, the ramps 60 substitute for the roller 26 in FIGS. 1 through 3. When the stylus 36 is inserted into one of the slots 40, it will engage an inserted card in the area of the rectangular chip and force the same against the ramp 60 so that the chip will be clamped between one of the ramps 60 and the punch. As the stylus is forced into the slot 40, it is also cammed downwardly on the ramp 60 thereby stripping the chip from the card and at the same time advancing the card to the next succeeding scored chip area for a subsequent punching operation. The ramps 60 may be resilient to flex and take up some of the shock of the stylus. The punch 54 of the stylus 36 need not be spring biased in view of the flexing of the ramps 60.

FIGS. 6 AND 7

FIGS. 6 and 7 illustrate yet another modification of the invention in which the stylus is eliminated and a series of fingers 62 which are resilient and flexible are each provided with a punch 64 which is mounted to pivot in an opening 66 in the finger 62. The punches are provided with naillike heads 68

which prevent the punches 64 from dropping through the openings 66.

It will be noted in FIG. 6 that upon depression of the finger 62 to the dotted line position, the punch 64 will pivot forwardly and downwardly on the roller 26 to both strip the chip 52 from the card C and advance the card for the next chip removing operation.

FIGS. 8, 9, AND 10

FIGS. 8, 9, and 10 illustrate yet another punching mechanism in which a series of flexible fingers 70 replace the fingers 62 of FIGS. 6 and 7. The fingers 70 are provided with punches 72. Buttons 74 permit depression of the spring fingers 70 which are formed from a single sheet of material so that they are all interconnected electrically to a single electrical connection 76 which is tied in to a lead wire 78. It is to be noted that the punches 72 include a stop tab 80. Mounted in the walls of the card holder is a feed lever 82 having a cam surface 84 and a feed dog 86. A spring 88 biases the feed lever forwardly and is connected to a wall 20 of the card holder H.

A locking bar 90 extends between a pair of the feed levers 82 as best illustrated in FIG. 10.

Mounted just behind the buttons 74 and above the fingers 70 is a rocking bar 92. The rocking bar is journaled in the sidewalls of the card holder H. A rocking arm 94 is secured to the rocking bar 92 and extends forwardly of the rocking bar 92 and beneath the fingers 70. A feed lever arm 96 is also connected to the rocking bar 92 and extends rearwardly of the rocking bar 92 and beneath the feed fingers 70 and connects to the feed levers 82 on either side of the card holder H. A series of contact conductors 98 are positioned below the stop tabs 80 and are provided with a series of leads 100 which junction in a multiple outlet 102 as does also the lead wire 78.

OPERATION OF FIGS. 8 THROUGH 10

It will now be obvious that upon the depression of the buttons 74 one of the spring fingers 70 will be depressed and the punch 72 will enter the slot 40 for the purpose of striking out one of the chips of a card (not shown). As the finger is depressed, it will cause a rocking of the rocking arm 94 downward and in turn will cause a rocking of the rocking bar 92 which in turn will cause a rocking of the feed lever arm 96. The rocking of the feed lever arm 96 will cause a reciprocation of the feed lever 82 rearwardly so as to cam the surface 84 over notches or openings in a card (not shown) which has been provided for scoring purposes. As the punch 72 descends, and the feed lever 82 reciprocates rearwardly, the locking bar 90 mounted between the feed levers 82, will move rearwardly and beneath the stop tabs 80 of the punches 72 which have not been depressed thereby insuring that these punches will not be depressed while the other punch is depressed. It will be noted that the punch which is depressed as illustrated in FIG. 10, in its downward travel, causes the tab 80 which also doubles as an electrical contact, to engage the electrical contact 98 completing a circuit between the fingers 70, the electrical connection 76, the lead wire 78, and with the lead 100. The outlet 102 is plugged into an indicating device (not shown) which will indicate which of the buttons 74 have been depressed and automatically score electrically in a unit (not shown). Upon release of the button 74, the feed dog 86 will engage one of the feed holes or slots in the card for advancing the card to the next position for subsequent punching operation. The spring 88 will cause retraction of the feed levers 82 upon release of the button 74.

FIGS. 11 THROUGH 14

FIGS. 11 through 14 show a modified type of punch mechanism in which the feed of the card, is prior to the punch stroke rather than after the punch stroke as illustrated in FIGS. 8, 9, 10. In FIGS. 11 through 14, the punch arms 104 include buttons 106 and punches 108. A rocking bar 110 is provided in advance of the punch arms 104 and is mounted to

the sidewalls 20 and 22. The rocking bar includes a locking arm 112 and a cam arm 114. Depending from the rocking bar 110 are rocking levers 116 which engage the card feed yoke member 118. The card feed yoke member 118 includes pawl feed fingers 120. The punch arms 104 include cam surfaces 122. The card feed yoke 118 is spring biased rearwardly by means of a spring 124. In operation, upon depression of one of the buttons 106, the cam surface 122 operates against the cam arm 114 of the rocking bar 110, to cam it forwardly and at the same time to cause the locking arm 112 to move beneath the projecting fingers 126 of the punch arms 104. When the rocking bar is rocked, the rocking levers 116 move forwardly engaging the card feed yoke 118 causing the pawl fingers 120 to engage in openings previously provided in special cards so as to index the cards forwardly to the next station. Upon further depression of the punch 106, the chips are forced out of the card by means of one of the punches 108. The action of spring 124 returns the rocking bar to its original position so that the cam arm 114 engages in the cam slot 128 upon release of the button 106.

FIG. 15 TO FIG. 18

FIG. 15 illustrates still another modification of the invention in which a slotted feed roll 130 as best illustrated in FIG. 16 is provided. The feed roll 130 is provided with a series of annular friction feed rings 132. Slots 134 are provided in the rotor at spaced intervals for permission of entry of the punches 136. The punches 136, which are mounted on arms 138, force the chips into the slots 134 thereby stripping them from the cards which have been inserted into the mechanism in a manner heretofore described.

The friction feed rings engage the undersurface of the cards to advance the same for positioning beneath the punches 136. When the chip has been forced by the punch into the slots 134, the slots provide a gripping action and maintain the chips within the slots until stripped therefrom by means of stripping fingers 140 which extend into the slots and force the chips therefrom and into the chip receptacle provided. The punches 136 fold the chips in U-shapes between the walls of the slots 134 to cause them to be frictionally engaged thereby due to the spring action of the folded chip.

The punch arms 138 are provided with a slot 142 which receives a rivet 144 connected to the punch 136. The punch 136 is biased to the rear of the slot 142 by means of a spring 146 attached to the rivet 144. In operation, one of the buttons 148 of the punches 136 is depressed. As the punch 136 enters into the slot 134 of the roller 130, the punch 136 moves forwardly as the rivet 144 travels forwardly in the slot 142 against the spring 146. Upon release of the button 148, the rivet returns to the rear of the slot bringing with it the punch 136. This action permits the punch 136 to act as the means for feeding and indexing the card to the next succeeding position for subsequent operation.

FIG. 19

FIG. 19 illustrates how any one of the card holders H heretofore described, can be equipped with a second punch mechanism generally indicated at 150. This punch mechanism is located in the bottom of the card holder and includes a spring identifying punch arm 152 with a series of punches 154 mounted thereon. A slot 156 is provided in the card holder H for receiving a card. A stop 158 limits the insertion of the card into the slot 156. Upon insertion of a card into the slot 156, the punch arm 152 is depressed upwardly causing the series of punches 154 to punch the identifying information into the card. The card is backed by a sponge or resilient backing material 160 against which the series of punches force the chips so that they will be stripped from the card.

While the invention has been described, it will be understood that it is capable of further modifications, and this application is intended to cover any variations, uses or adaptations of the invention following in general the principles of the

invention and including such departures from the present disclosure as come within known or customary practice in the art to which the invention pertains, and as may be applied to the essential features hereinbefore set forth and as fall within the scope of the invention or the limits of the appended claims.

I claim:

1. A scoring device for punching and removing chips from computer punch cards comprising:
  - a. a card support means;
  - b. a cover means for said card support means;
  - c. said card support means and cover means forming a slot for receiving a computer punch card;
  - d. means associated with said card support and cover means for guiding a card between said card support and cover means;
  - e. means mounted beneath said card support means for collecting said chips;
  - f. means for aligning a card in an initial predetermined position within said slot;
  - g. means in said cover for receiving a punch;
  - h. means associated with said support means cooperating with said punch for holding said chips against said punch during movement of said punch;
  - i. means cooperating with said punch for advancing said card from said initial predetermined position to a second predetermined position; and
  - j. means for limiting the travel of said punch during punching operations.
2. A scoring device as in claim 1 wherein said means for holding said chips against said punch during movement of said punch includes a pressure receiving platen.
3. A scoring device as in claim 2 and wherein said platen includes a resilient roller.
4. A scoring device as in claim 3 and wherein said roller is actuated by said punch.
5. A scoring device as in claim 1 and wherein said means for holding said chips against said punch during movement of said punch includes a roller.
6. A scoring device as in claim 5 and wherein said roller is recessed to receive said punch.
7. A scoring device as in claim 2 and wherein said platen comprises a ramp angled downwardly from said support means.
8. A scoring device as in claim 7 and wherein said ramp is resilient.
9. A scoring device as in claim 8 and wherein said ramp includes a V-shaped groove.
10. A scoring device as in claim 1 and wherein said means in said cover for receiving said punch cover comprises an elongate slot.
11. A scoring device as in claim 5 and wherein said roller is mounted beneath said means in said cover for receiving said punch.
12. A scoring device as in claim 11 and including friction means on said roller for gripping said card for advancing said card upon rotation of said roller.
13. A scoring device as in claim 11 and wherein said roller is positioned to contact a card inserted into said slot and to advance said card upon actuation thereof.
14. A scoring device as in claim 1 and including a punch.
15. A scoring device as in claim 14 and wherein said punch includes means for advancing a card.
16. A scoring device as in claim 6 and wherein said recess is an annular slot.
17. A scoring device as in claim 16 and including a chip remover for said slot.
18. A scoring device as in claim 17 and wherein said chip remover includes a spring finger extending into said slot.
19. A scoring device as in claim 1 and including:
  - a. a plurality of said punches mounted on said device; and
  - b. including a plurality of said means cooperating with said punches for holding said chips against said punches during movement of said punches.

20. A scoring device as in claim 19 and including electrical means associated with each of said punches for connection to a tabulating mechanism.

21. A scoring device as in claim 19 and wherein said means for advancing said card includes a lever and pawl mechanism.

22. A scoring device as in claim 21 and wherein said plurality of punches each include cam means for operating said lever and pawl mechanism.

23. A scoring device as in claim 22 and including means for locking the remainder of a said punches upon operation of one punch.

24. A scoring device as in claim 23 and wherein said locking means includes a transverse lock bar.

25. A scoring device as in claim 21 and wherein said lever and pawl mechanisms are spring biased.

26. A scoring device as in claim 20 and wherein said electrical means includes individual contact means associated with each of said punches.

27. A scoring device as in claim 19 and wherein said punches include a series of resilient fingers integrally connected to a base member.

28. A scoring device as in claim 14 and including a plurality of means in said cover for receiving said punch.

29. A scoring device as in claim 28 and wherein:

a. said plurality of means in said cover includes a parallel series of slots;

b. said series extending transversely to the direction of travel of said card.

30. A scoring device as in claim 29 and wherein each of said slots are coextensive with each other.

31. A scoring device as in claim 30 and wherein said slots are spaced from each other a distance equal to twice the distance of parallel adjacent chips in said cards.

32. A scoring device as in claim 31 and including second

scoring means on said device for punching upwardly into a card.

33. A scoring device as in claim 31 and wherein said second scoring means includes spring return means.

34. A scoring device as in claim 33 and including second slot in said device for receiving a card for punching by means of said second scoring means.

35. A scoring device as in claim 34 and including indicia means mounted above said cover means.

36. A scoring device as in claim 35 and wherein said indicia means is changeable.

37. A scoring device as in claim 14 and wherein said punch is spring biased and pivotable.

38. A scoring device for punching and removing chips from computer punch cards comprising:

a. a card support means;

b. a cover means for said card support means;

c. said card support means and cover means forming a slot for receiving a computer punch card;

d. means associated with said card support and cover means for guiding a card between said card support and cover means;

e. means for aligning a card in initial predetermined position within said slot;

f. means in said cover for receiving a punch;

g. means associated with said support means for holding said chips against said punch during movement of said punch;

h. means cooperating with said punch for advancing said card from said initial predetermined position to a second predetermined position; and

i. means for limiting the travel of said punch during punching operation.
